[57] **CLAIM**

The ornamental design for an electronic circuit setup station for education and training, as shown and described.

DESCRIPTION

FIG. 1 is a left side elevational view of an electronic circuit setup station for education and training showing my new design;

FIG. 2 is a view thereof taken along line 2—2 of FIG. 1. For the purpose of a complete disclosure, the breadboard socket panel is shown partially cut away to reveal the velcro mounting strips shown in FIGS. 1 and 3; FIG. 3 is a right side elevational view thereof; FIG. 4 is a rear elevational view thereof; FIG. 5 is a bottom view thereof; and,

FIG. 6 is a view of an electronic setup station taken along a line in a second embodiment corresponding to line 2—2 of FIG. 1. The second embodiment is the same as the first except the velcro mounted breadboard panel is replaced with a screw mounted circuit panel.
